UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed November 28, 1923. Serial No. 677,361.

To all whom it may concern:

Be it known that I, GEORGE A. SEIB, citizen of the United States, and resident of Ilion, in the county of Herkimer and State 5 of New York, have invented certain new and useful Improvements in Typewriting Machines, of which the following is a specification.

My invention relates to typewriting machines and more particularly to type actions therefor.

The main object of my invention, generally stated, is to provide a light operating and highly efficient type action.

15 To the above and other ends which will hereinafter appear, my invention consists in the features of construction, combinations of devices and arrangements of parts herein-after described and particularly pointed out 20 in the appended claims.

Figure 1 of the drawing is a fragmentary fore-and-aft vertical sectional view of a typewriting machine embodying my invention.

25 Figure 2 is an enlarged detail fragmentary sectional view showing a slightly modified form of construction.

I have shown my invention embodied in a standard Remington machine, only so much 30 of said machine being shown as is necessary to arrive at an understanding of the invention. It should be understood, however, that the invention may be embodied in other styles of typewriting machines and that 35 various changes may be made to facilitate such embodiment.

The frame of the machine comprises a base 1, corner posts 2 and a top plate 3. The usual carriage (not shown) carries a 40 platen 4 and is controlled in its letter feed movement by escapement mechanism controlled through intermediate connections 5, 6 and 7 from a universal bar 8. The universal bar is returned, or moved forward, 45 from its actuated position by a spring 9 connected at one end to an adjustable bracket arm 10 and at its opposite end 11 to the crank arm 6.

Each actuation of a printing key not only 50 controls the escapement mechanism but also the usual ribbon vibrator mechanism which includes a separate universal bar 12, rock shaft 13, crank arm 14 and lever-like pivoted frame 15 operatively connected with 55 the ribbon vibrator.

Printing key levers 16 are constructed and mounted in the usual manner, and actuate type bars 17, each lever being provided with a finger key 18 and a returning spring 19. Each key lever has an upwardly extending 60 member 20 that carries a laterally projecting pin 21 received in a slot 22 in an angular sub-lever 23. The levers 23 are mounted in the usual manner on a pivot wire 24 supported on a slotted fixed cross bar 25. The 65 type bars 17 are segmentally arranged and mounted on a pivot wire 26 in a slotted type bar segment 27 to strike upwardly and rearwardly against the front face of the platen 4. The heel of each type bar is formed with 70 a contact member 28 adapted to coact with the front edge of the segmental universal bar 8 and move the latter rearwardly against the force of the spring 9, and thus 75 control the carriage escapement. So far as 75 described the parts are of the usual construction embodied in standard Remington machines.

As shown in the present instance, however, the upper end portion of each angular 80 sublever is slotted longitudinally at 29 to receive with a close sliding fit a headed pin 30 that projects laterally from the heel of the associated type bar 17 and forms an interlocking connection therewith. The 85 construction and relative arrangement of the parts of each type action are such that on the depression of a finger key 18 from the normal dot-and-dash to the full line position shown in Fig. 1, the following operation of 90 the parts takes place: In the normal position of the parts the longitudinal slot 29 in each sublever 23 extends transversely of the direction of the motion of the associated pin 30. Therefore, the movement of each sublever 95 from normal position will cause a movement of the associated type bar towards the printing position, the key lever, sublever and type bar moving simultaneously. This key controlled operating movement of the type bar will continue until the parts reach the full line position shown in 100 this figure. It will be seen that at this time relative arrangement of the parts has been 105 changed so that the slot 29 extends longitudinally in the general direction of the travel of the pin 30 from this point to the dotted line printing position of the type bar. It also will be seen that when the parts are 110 in the full line position shown in Fig. 1 the

sublever under key depression ceases to exert an operating force on the type bar, working as it does at this time with a dead center pull against the pivot 26 of the type bar, as indicated by the line *a* in Figs. 1 and 2. This, therefore, limits the depression of the key lever and the operating movement of the sublever beyond the positions shown in full lines in Fig. 1. Notwithstanding this arrest of the key lever and sublever a further movement of the type bar to the dotted line printing position is effected. This is due to the overthrow of the type bar by the momentum it has acquired from the depression of the finger key; such overthrow movement of the bar being permitted by the movement of the pin 30 along the slot 29, acting at this time substantially as a lost motion connection. It will be seen that this overthrow movement of the type bar after the operating movement of the finger key and the intermediate actuating connections or devices have been arrested, is brought about after the type bar has been moved by said key and connections close to the printing position, and the type bar has acquired a high speed. The overthrow movement of the type bar from the full to the dotted line printing position in Fig. 1 is therefore effected entirely by its own momentum and without restraint from the finger key and sublever except for a slight camming action of the pin 30 against a wall of the slot 29 at the last part of the movement of the type bar. This tends to pull the sublever back and elevate the key lever and in practice aids in giving a quick return to the type bar, as well as to reduce the striking force of the type against the paper.

Should the finger key be depressed very slowly it would result in moving the type bar only to full line position in Fig. 1, but in the ordinary operation of the key the type bar overthrows beyond this position to the printing point.

In practice I prefer to dispense with the usual anvil on the type bar segment and against which it is customary to have each type bar strike just prior to making an imprint. This anvil may be readily dispensed with in the present construction since it is impossible to hold a type bar against the platen by pressure exerted on the finger key, and it is therefore impossible to cause blurred imprints or "ghosts" by holding the type bar against the platen when it is in motion.

The manner of arresting the depression of the key by movement of the actuating parts to the full line position in Fig. 1, and through the actuating parts themselves, provides an easy acting cushioning arrest agreeable to the operator.

The overthrow movement of the type bar from the full to the dotted line position in

Fig. 1 is made against the force of the spring 9 by which the universal bar is returned, and the reaction of this spring and the rebound of the type bar from the platen is effective to quickly return the type bar from the dotted to, or slightly beyond, the full line position even should the operator maintain the finger key 18 depressed.

Should it be found desirable to obtain a greater extent of retardation of the type bar as it overthrows beyond the line *a*, then the slot 29 may be slightly modified as indicated in Fig. 2. From a consideration of this figure it will be understood that the side walls of that portion 29^a of the slot 29 in each sublever at and upwardly beyond where the associated pin 30 rests when in the full line Fig. 1 position may be slightly curved away from the type bar pivot 26 as the parts appear in the full line position. This is clearly indicated in Fig. 2 from which it will be seen that upwardly beyond the position indicated by the dotted line *a* the walls of the slot 29 are curved at 29^a on arcs represented by the dotted lines *b*. When the Fig. 2 position is reached the slightly curved rear wall 29^a acts as a cam tending to more materially resist the movement of the bar from the full to the dotted line position in Fig. 1. During this overthrow motion of the type bar, the sublever is pulled back and the key lever elevated slightly. In practice, however, I prefer to have the side walls of the slot 29 in each sublever made straight throughout as in Fig. 1.

In view of the fact that the type bar moves to the printing position and immediately returns therefrom to the full line position even though the operator maintains the printing key depressed, an escapement with any desired extent of "drop" for the carriage up to a full drop or "reverse" feed, may be provided without the possibility of holding the type bar against the platen while it is in motion, which would result in producing blurred imprints or "ghosts." The construction therefore accommodates itself not only to different characters of escapements but also to the touch of the operator, whether it be a long following stroke or a short quick stroke.

It will be understood, moreover, that the universal bar 12 for the ribbon vibrator necessarily completes its stroke and moves the ribbon in the path of the approaching type bar, by the time the latter moves to the full line position in Fig. 1. Therefore, the ribbon may be held against movement in its actuated position while the type bar is moving from the full to the dotted line position in Fig. 1, thus insuring a proper positioning of the ribbon.

Inasmuch as a type bar cannot be held under key depression in the type bar center

guide 31; but moves quickly into and out of said guide from the full to the dotted line position in Fig. 1 and vice versa, there is less liability of a type bar sticking in the 5 guide than when the type bar is positively moved under the key depression into the guide and all the way to the printing position.

- By the elimination of the type bar anvil 10 I not only dispense with the noise ordinarily incident to the type bars striking such anvil, but also reduce the cost of manufacture and the additional aligning costs incidental to the use of an anvil.
- 15 The present construction is such that it lends itself to ready embodiment in standard Remington machines with but little change except the modification of sublevers and type bars as shown herein, and the removal of the anvil when desired.

20 While I have described my invention with considerable detail in the particular embodiments thereof shown in the present instance, it should be understood that various changes 25 may be made without departing from the invention as it is defined in the accompanying claims.

What I claim as new and desire to secure 30 by Letters Patent, is:

35 1. In a type action for typewriting machines, the combination of a type bar that turns always on a single fixed pivot, a finger key, and intermediate actuating connections which include a close sliding fit pin and slot connection between the type bar and one of its actuating members which limits the depression of the key before the type bar reaches the printing position.

40 2. In a type action for typewriting machines, the combination of a type bar that always turns on a single fixed pivot, a finger key, and constantly maintained intermediate actuating connections which include a pin and slot connection between the type bar and one of its actuating members which limits the depression of the key before the type bar reaches the printing position and enables the type bar by its momentum to travel the remainder of the distance to the 45 printing position.

50 3. In a type action for typewriting machines, the combination of a type bar, a key lever, and intermediate actuating connections between said key lever and type bar which include a pin-and-slot connection that varies its relation so as to substantially dead center the parts at said pin-and-slot connection and thus enable the type bar to travel independently to the printing point by its own momentum after the depression of the key has been arrested.

55 4. In a type action for typewriting machines, the combination of a type bar, a key actuated lever therefor, and a pin and slot connection between the type bar and lever

that limits the actuation of the lever but permits the type bar to travel to the printing point by its momentum after the lever has been arrested in its operating movement.

5. In a type action for typewriting machines, the combination of a pivoted type bar carrying a pin, and a key actuated lever having a slot in which said pin works, the construction and relation of the parts being such that the lever operates with a dead center pull against the pivot of the type bar and has its operating movement thus limited while the type bar completes its movement to the printing point by its own momentum after said key actuated lever has been arrested in its operating movement.

6. In a type action for typewriting machines, the combination of a type bar, a key, and intermediate actuating connections between the key and type bar including a pin and slot connection, the parts being constructed and arranged so that the walls of the slot extend transversely of the direction of travel of the pin at the first portion of the stroke of the key and extend longitudinally in the general direction of travel of the pin later in the stroke so that the type bar may overthrow and complete its travel to the printing point by its own momentum.

7. In a type action for typewriting machines, the combination of a pivoted type bar, a key lever, an intermediate sublever having a slot therein, and a pin on the type bar which works in the slot in the sublever, the construction and arrangement of the parts being such that the walls of said slot extend transversely of the direction of travel of said pin during the first portion of the key depression and the sublever pulls against the pivot of the type bar before the latter has completed its printing movement thereby limiting the depression of the key lever and at which time the walls of said slot are disposed in the general direction of the travel of the pin to permit an overthrow movement of the type bar under its own momentum.

8. In a type action for typewriting machines, the combination of a pivoted type bar provided with a pin at its heel and a key actuated sublever arrested by the pivot of the type bar and formed with a slot to embrace said pin and drive said type bar positively a limited distance, said slot being prolonged to permit said type bar to travel alone the remainder of its required distance by overthrow.

9. In a typewriting machine, the combination of an upwardly and rearwardly striking type bar, a spring returned universal bar which is actuated by said type bar, a finger key, and intermediate actuating connections between said type bar and finger key including a pin and slot connection that operates positively on the key depression to

move the type bar towards the printing position and at the last portion of the movement of the bar acts substantially as a lost motion connection to enable the type bar to 5 complete its movement to printing position by its own momentum.

10. In a typewriting machine, the combination of a type bar, a key lever, intermediate actuating connections between the type 10 bar and key lever including a sub-lever and a pin and slot connection between the type bar and sub-lever by which the key lever is limited in its depression before the type bar reaches the printing position, the type 15 bar thereafter completing its stroke by overthrow due to its own momentum, and a universal bar for a ribbon vibrator actuated directly by the key lever and completing its movement before the said overthrow movement of the type bar takes place.

11. In a typewriting machine, the combination of a type bar, a spring returned universal bar for a carriage escapement, a finger key, intermediate actuating connections 25 between said type bar and finger key including a pin and slot connection by which the finger key is limited in its depression before the type bar reaches the printing position, the type bar thereafter completing its stroke 30 by an overthrow movement due to its own momentum, and a second universal bar for

a ribbon vibrator actuated by said finger key and completing its movement before said overthrow movement of the type bar takes place.

35

12. In a typewriting machine, the combination of a pivoted type bar having a pin at its heel, and a key actuated sublever having a slot embracing said pin; the sublever being arranged to be arrested by the type 40 bar pivot before the type bar arrives at the printing position and the said slot being long enough to enable the type bar thereafter to complete its printing motion by momentum.

45

13. In a typewriting machine, the combination of a pivoted type bar having a pin at its heel and a key actuated sublever having a slot embracing said pin; the sublever being arranged to be arrested by the type bar pivot before the type bar arrives at the printing 50 position, the said slot being long enough to enable the type bar thereafter to complete its printing motion by momentum and the end of said slot being so related to said pin during the overthrow movement of the type bar as that the pin has a reverse camming action 55 on said sublever.

Signed at Ilion, in the county of Herkimer, and State of New York this 23 day of November, A. D. 1923.

GEORGE A. SEIB.
